UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

STOP FOR WEIGHTS OF MULTIPLE-NEEDLE DETECTORS.

Application filed December 21, 1925. Serial No. 76,823.

This invention relates to improvements in the multiple needle detectors for looms of the general type set forth in Patents Nos. 1,549,960 and 1,583,135 and it is the general object 5 of the invention to prevent undesirable movement of the weights which are used for the individual needles.

In the co-pending application there is shown a feeler of the multiple needle type 10 having weights, one for each needle, the effect of which is to cause light pressure on the needles to move them through a very thin layer of yarn. When a loom equipped with a detector of this type is running at a comparatively high rate of speed it is found that 15 the weights swing abnormally about their pivots, striking the hub of the transerrer arm immediately above the detector and resulting in objectionable deforming of the weights. This excess movement of the 20 weights carries them away from the needles and as they rebound from the transerrer arm they give the needles a blow which will drive them into a full bobbin with resultant 25 wearing or through a thin layer of yarn and into one of several holes formed in the barrel of the bobbin, causing premature indication of substantial weft exhaustion. It is also found that under certain conditions the upper 30 ends of the needles are forced against the actuating lever as the same moves downwardly, scoring said lever and rendering its operation inaccurate. It is an important object of my invention to restrain excess movement of the weights to the end that the 35 objections mentioned may be overcome.

It is a further object of my invention to improve the weights shown in the aforesaid application and adapt the spring supporting bracket of the aforesaid patent to cooperate with the improved weights to prevent excess movement thereof.

With these and other objects in view which will appear as the description proceeds, 45 my invention resides in the combination and arrangement of parts hereinafter described and set forth in the claims.

In the accompanying drawings wherein a 50 convenient embodiment of my invention is shown,

Fig. 1 is an end elevation of a detector partly in section showing my invention applied thereto,

Fig. 2 is a perspective view of one of the 55 weights, and

Fig. 3 is a detail horizontal section on line 3—3 of Fig. 1.

Referring to the drawings it will be seen that I have provided a detector stand 10 which may be secured to the loom in any 60 approved manner and said stand has bolted thereto a support 11 provided with a wedged rib 12 to enter a complementarily formed notch or groove in the lower rear face of the needle carrier 13. Said carrier has a plurality of needles 14 mounted therein for free 65 sliding movement each of which has a yarn engaging tip 15 and an indicating end 16. The ends 16 cooperate with an actuator 17 which communicates the indication to the 70 weft replenishing mechanism, not shown. In order to return the needles 14 to their proper detecting position the upright portions 18 thereof are each engaged by a weight 19 pivoted for free motion on a stud 20 secured 75 to a lug 21 preferably formed integrally with the carrier 13. A needle withdrawing member 22 is also pivoted on the stud 20 and is provided with an arm 23 which as shown 80 in Fig. 3 extends behind the upright portions of all the needles 14. Said member 22 is further provided with an ear 24 to be engaged by a part of the transfer mechanism (not shown) by means of which the arm 23 may be moved forwardly at the time of 85 transfer to withdraw the ends 15 from the path of the incoming bobbin.

Extending forwardly from and secured to the carrier 13 is a sheet steel bracket 25 to the forward end of which is attached a tension spring 26 the rear end of which extends through the carrier 13 and support 11 and is retained by a pin 27 which bridges the opening in support 11. In this way the carrier 13 is mounted for yielding forward 95 movement against the tension of spring 26. The bracket 25 has an upper shelf 28 terminating at its forward end in an upbent end 29. The matter thus far described is substantially the same as that shown in the 100 aforesaid patent and application and forms no part of my present invention.

In carrying out my improvements I provide each of the weights 19 with a depending finger 30 and I further provide the upbent end 29 with a shock absorbing pad 33 105

formed of suitable material, such as leather. I also provide the withdrawing member 22 with an arm 34 which is connected to a tension spring 35 the lower end of which is fastened to the bracket 25. Said spring serves to position the arm 23 and ear 24.

In operation the weights will normally be in the position indicated in full lines in Fig. 1, and as bobbin W advances it will engage the rear ends of the needles and move the same forwardly. If the bobbin is full its advancing surface will move to the dotted line position shown in Fig. 1, and the needles and weights will move to the dot and dash line position. It will be seen that in this position fingers 30 engage the shock absorbing pad 33 to prevent excess movement of the weights. The latter therefore do not move to a position from which they can descend and strike the needles to force the same against a yarn surface or through relatively thin layers of weft. The spring 35 moves with the carrier 13 and serves to position the withdrawing member 22 properly with respect to the needles.

From the foregoing it will be seen that I have provided a weft detector of the multiple needle type having weights so controlled as to prevent excess movement thereof so that the needles are not struck to wear the yarn of a full bobbin or penetrate a thin layer of weft. Furthermore, it will be seen that the shock absorbing pad serves the double function of limiting forward movement of the needles and also the weights and that said pad moves with the stud 20 to be operative in all positions of the carrier 13 to prevent improper movement of the needles and weights.

Having thus described my invention it will be apparent that changes and modifications may be made therein by those skilled in the art without departing from the spirit and scope of the invention, and I do not wish to be limited to the details herein disclosed but what I claim is:

1. In a weft detector for looms, a carrier, a plurality of needle detectors slidably mounted in the carrier, a plurality of weights one for each needle detector to hold said needles rearwardly in engagement with the yarn to be detected, a stop mounted on the carrier, and a finger extending from each weight to engage the stop when said weights are moved forwardly by the needles, said stop preventing excess movement of the weights beyond the position corresponding to the foremost position assumed by the needle detectors. 50

2. In a weft detector for looms, a carrier, a plurality of needle detectors slidably mounted on the carrier, a weight for each needle detector to hold the same yieldingly in engagement with the surface to be detected, a stop mounted on the carrier and 60 having a yielding surface, and a finger formed on each weight and positioned to engage the yielding surface when the weights are moved beyond the position corresponding to the foremost position assumed 70 by the needle detectors.

3. In a weft detector for looms, a carrier, a plurality of needle detectors movable on said carrier, a weight for each needle detector to hold the same yieldingly in engagement with the yarn to be detected, a finger depending from each weight, a support on which said carrier is movably mounted, and a stop movable with the carrier in all of its positions to engage and 80 prevent excess movement of the weights beyond the position corresponding to the foremost position assumed by the needle detectors. 75

4. A weight for a multiple needle weft 85 detector, said weight having an opening to receive a stud and having a portion to engage a needle detector and having also a finger to engage a stop.

In testimony whereof I have hereunto 90 affixed my signature.

ALBERT A. GORDON.
